Primary Examiner — Mary Ann Calabrese*Assistant Examiner* — Mark David Wolfley(74) *Attorney, Agent, or Firm* — Shumaker, Loop & Kendrick, LLP; S. Alexander Long, Jr.(57) **CLAIM**

The ornamental design for a vehicular seating suite, as shown and described.

DESCRIPTION

FIG. 1 is a top, front, right perspective view of a vehicular seating suite showing my new design;

FIG. 2 is a front elevational view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines are included for the purpose of illustrating portions of the vehicular seating suite that form no part of the claimed design.

1 Claim, 7 Drawing Sheets(56)
